[57] CLAIM

The ornamental design for combined cap and mosquito net, as shown and described.

DESCRIPTION

FIG. 1 is a perspective view of the combined cap and mosquito net;

FIG. 2 is a top plan view of the cap of FIG. 1, the bottom plan view is plane and unornamented;

FIG. 3 is a side elevational view of the cap of FIG. 1; FIG. 4 is a front elevational view of the cap of FIG. 1; FIG. 5 is a perspective view of the cap of FIG. 1 with the mosquito net unfolded and surrounding the cap;

FIG. 6 is a top plan view of the cap of FIG. 5;

FIG. 7 is a side elevational view of the cap of FIG. 5;

FIG. 8 is a front elevational view of the cap of FIG. 5;

FIG. 9 is a second embodiment of the combined cap and mosquito net showing my new design, the difference being the strapless front pouch;

FIG. 10 is a top plan view of the cap of FIG. 9, the bottom plan view is plane and unornamented;

FIG. 11 is a side elevational view of the cap of FIG. 9;

FIG. 12 is a front elevational view of the cap of FIG. 9;

FIG. 13 is a perspective view of the cap of FIG. 9 with the mosquito net unfolded and surrounding the cap;

FIG. 14 is a top plan view of the cap of FIG. 9;

FIG. 15 is a side elevational view of the cap of FIG. 9; and,

FIG. 16 is a front elevational view of the cap of FIG. 9.
